UNITED STATES PATENT OFFICE.

CRAIG MURRAY, OF KALAMAZOO, ASSIGNOR TO SPENCER J. WING, OF SCHOOLCRAFT, MICHIGAN.

WHEEL-HARROW.

SPECIFICATION forming part of Letters Patent No. 268,267, dated November 28, 1882.

Application filed July 3, 1882. (No model.)

To all whom it may concern:

Be it known that I, CRAIG MURRAY, of Kalamazoo, in the county of Kalamazoo and State of Michigan, have invented certain new useful Improvements in Wheel-Harrows; and I do hereby declare the following to be a full, clear, and exact description of the invention, such as will enable others skilled in the art to which it pertains to make and use the same.

10 My invention relates to wheel-harrows, the object being to provide a harrow which will combine strength and economy of construction with ease of operation and durability in use.

15 The invention consists in the improved construction and combinations of parts herein-after fully set forth, and pointed out in the claims.

20 In the drawings, Figure 1 represents a side elevation of a harrow constructed in accordance with my invention. Fig. 2 is a plan view of the same, partially broken away. Figs. 3, 4, 5, 6, 7, 8, 9, and 10 represent parts in detail.

25 B represents the axle of the harrow, to each end of which is secured a crank-arm, a' , by means of a bolt, A, passing longitudinally into the axle, which latter is slotted to receive a nut, a^2 ; or the crank-arms may be secured in any other suitable manner.

30 To the under side of the axle B are securely bolted any desired number of curved or straight cross-arms, a , for supporting the tooth-shafts D of the machine. As shown in the drawings, I prefer to employ four of these arms a —one at each end of the axle B, and two near the center 35 of the latter. The tooth-shafts are secured to the ends of these arms by means of clips and bolts d d' . These shafts D may be formed of one piece extending entirely across the machine, or they may be of two separate sections, as 40 shown in Fig. 2, and the harrow-teeth are secured thereto in the manner hereinafter described.

45 c represents a sector, provided with an inwardly-projecting flange, c' , by means of which the sector is secured (one at each end of the axle) to the axle by the same bolt or bolts that secure the end cross-arm, a , thereto. The sectors are each arranged between the end of the axle and the crank-arm a' , and are also held by

the bolt A, which secures the crank-arm in place.

H represents a lifting-lever, consisting of two parallel bars, h h , supporting at their upper ends an inwardly-projecting handle, c'' , while the lower ends, nn , of said bars are curved 55 or pronged to adapt them to enter slots or grooves n' n' , formed in the upper end of the crank-arm a' .

Between the bars nn of the lever is arranged a sliding dog, e , flanged or grooved to retain it in position and provided with a rod, r , which extends through a perforated bracket, r' , secured to the bars, and terminates in a bent handle, f . A spiral spring, r^2 , surrounds the upper end of the rod r , the lower end of said 65 spring bearing against a flange or collar, r^3 , of the rod, while the opposite end of the spring bears against the bracket r' .

x represents the spindle of the axle—one at each end—upon which the carrying-wheels are 70 mounted.

P represents a two-part pole, secured to the axle B by means of metallic strips p , embracing the axle.

S represents a seat, secured upon a support, 75 g , whose lower end is bolted securely between the two central cross-arms, a a . The seat-support is further held by means of a loop or bail, u , which surrounds the support, and whose ends are secured by bolts to the axle, while 80 the support g is secured to said bail by means of a bolt, u' , passing through the support and bail.

v represents a device or draft-link, secured to the under sides of the forward ends of the 85 center cross-arms.

L represent levers, secured by arms l to the forward tooth-shaft D, the joints of said levers being just in rear of the axle B. Said levers are also secured by arms l to the rear 90 tooth-shaft D, and are adapted to be held in an elevated position to hold the teeth clear of the ground by bent hooks y y , pivoted to the upper side of the axle.

Figs. 5, 7, and 10 represent the devices for 95 securing the teeth t and the arms l to their shafts. The reverse end of each tooth and arm passes about half around the shaft, and the

shank portion is provided with a slot, x' , to receive a bolt, and a hole or slot, x^2 , to receive the pin e of a clamping-washer, w . Said washer is curved or semicircular, straight or angular form, to conform to the shape of the shaft, and is serrated on its inner face to better adapt it to retain its position, and is slotted for adjusting the teeth and arms. The slotted or perforated end of each tooth and arm is secured by the engagement therewith of the lug or pin e of the washer, which latter is then secured by a bolt, i , passing through the slot in said washer and through the shaft and the slot x' of the tooth or arm, and secured by a nut, x^3 . By the means thus described the teeth and arms are securely held in place, but may be readily removed, when broken or unduly worn, by simply removing the bolt i .

The harrow, when constructed as above described, may be adjusted relative to the ground by means of the levers H , and the teeth may be raised by the levers L and held in raised position by the hooks y , as described, the hooks being suitably bent to engage or support said levers. Said levers L are provided with a series of perforations, x^4 , Fig. 1, to admit of the adjustment of the rear arm, l , to change the pitch of the teeth.

In Fig. 1, J represents a seeder supported on each side by an arm, m , the latter being secured to the front end of the adjacent arms D by the same bolt, d' , that fastens the clip d thereto.

Having fully described my invention, what I claim as new, and desire to secure by Letters Patent, is—

1. In a harrow, the combination, with the axle, of a crank-arm carrying a spindle, a sector, and a two-part lever having its inner end curved or pronged and adapted to enter curved slots or grooves of the crank-arm, substantially as set forth.

2. In a harrow, the combination, with the

tooth-supporting shaft, of a tooth provided with a hole or slot in its rear end, a perforated washer adapted to fit against the tooth-supporting shaft and provided with a lug that enters the hole in the tooth, and a bolt that passes through the washer, and a hole in that portion of the tooth which is on the opposite side of the shaft from the washer, and thus secures the parts in place, substantially as set forth.

3. In a harrow, the combination, with the tooth-supporting shaft, of a tooth provided with a hole at its rear end, a perforated washer provided with a serrated face adapted to fit against the tooth-supporting shaft and provided with a lug that enters the hole in the tooth, and a fastening-bolt that passes through the washer, shaft, and a hole in that portion of the tooth which is on the side of the shaft opposite the washer, substantially as set forth.

4. The combination, with the crank-axle and sector, of a lifting-lever consisting of two parallel bars having curved ends, secured in correspondingly-curved-grooves in the crank-arm, and a sliding dog arranged between said bars and provided with a handle, substantially as set forth.

5. The combination, with the tooth-shafts and an operating-lever, of an arm, l , a washer provided with a serrated face that fits against the tooth-shaft, and is provided with a lug that enters a hole in one end of said arm, and a fastening-bolt that passes through the washer, tooth-shaft, and said arm, substantially as set forth.

In testimony whereof I have signed this specification in the presence of two subscribing witnesses.

CRAIG MURRAY.
